ATTORNEY.

UNITED STATES PATENT OFFICE.

ANDREW ALLISON, JR., OF PHILADELPHIA, PENNSYLVANIA.

ELECTRIC ALARM FOR LETTER-HOLDERS.

SPECIFICATION forming part of Letters Patent No. 234,218, dated November 9, 1880.

Application filed September 13, 1880. (No model.)

To all whom it may concern:

Be it known that I, ANDREW ALLISON, Jr., a citizen of the United States, residing in the city and county of Philadelphia, and State 5 of Pennsylvania, have invented a new and useful Improvement in Electric Alarms for Holders, Boxes, &c., for Letters and other Articles, which improvement is fully set forth in the following specification and accompanying 10 drawings, in which—

Figure 1 is a top view of the alarm embodying my invention. Fig. 2 is a vertical section thereof in line *x x*. Fig. 3 is a vertical section of another form. Fig. 4 is a bottom view of the upper portion thereof. Fig. 15 5 is a side view of a hook or rack embodying my invention. Fig. 6 is a vertical section of a pigeon-hole or letter-box embodying my invention.

20 Similar letters of reference indicate corresponding parts in the several figures.

My invention consists of a holder, receiver, letter-box, &c., for letters, notes, messages, and other articles, which, when applied to the 25 former, sounds an electrically-operated alarm, thus directing attention to the article, (that it requires delivery or other service,) the alarm continuing until the article is removed, the work being accomplished on open or closed 30 circuits.

Referring to the drawings, A represents a base-piece adapted to be supported on a table, desk, &c., in a telegraph or other office or place of business, and B represents a cap-piece, which is secured to the top of the base 35 A and extends parallel therewith, the ends of one or both parts being flaring to admit of the insertion of letters, notes, messages, and other articles between them.

40 C represents a longitudinally-extending spring or springs secured to the under side of the cap B, and bearing freely against connecting points or plates D on the base A, to which electric wires E E are attached.

45 In Fig. 3 a longitudinally-extending spring, C, is secured centrally to a plate, D', on the under side of the cap B, and longitudinally-

extending springs C' are connected to the ends of said cap, the inner ends of the springs C' projecting toward the ends of the springs 50 C, so as to be brought thereagainst when raised or pressed.

Connection-plates D are attached to the outer ends on cap B, and in contact with the springs C'. To said plates D are connected 55 electric wires E, and to the plate D' also is connected an electric wire, E.

It will be noticed that in Fig. 2 I show a closed circuit, and in Figs. 3 and 4 an open 60 circuit.

When a letter, message, or other article is inserted between the ends of the cap B and base-piece A, Fig. 1, the spring C is lifted from the connection point or plate D, and the circuit is opened, thereby causing the ringing 65 of a bell or the sounding of other alarm.

When a letter, message, or other article is inserted between the ends of the cap B and base-piece A, Fig. 3, the spring C' is brought 70 in contact with the spring C, thus closing the circuit and causing a bell to be rung or alarm sounded.

In Fig. 5 I show a hook or rack, and in Fig. 6 a pigeon-hole or letter-box, both with open currents; but they may be constructed with 75 closed currents, their operations being similar to those described for Figs. 2 and 3, the letter, &c., if inserted between the hook or spring, Fig. 5, or pressed against the spring in the box or pigeon-hole, Fig. 6, causing an alarm, 80 which discontinues when the letter, &c., is removed.

Having thus described my invention, what I claim as new, and desire to secure by Letters Patent, is—

The combination of base-piece A and cap-piece B with interposed circuit-opening or circuit-closing springs, whereby the thrusting of a letter under one of said springs causes an alarm to sound, substantially as set forth.

ANDREW ALLISON, JR.
